UNITED STATES PATENT OFFICE.

ALONZO E. RHOADES AND ARTHUR S. JOHNSON, OF HOPEDALE, MASSACHUSETTS, AS
SIGNORS TO DRAPER CORPORATION, OF HOPEDALE, MASSACHUSETTS, A CORPORA-
TION OF MAINE.

YARN TENSION FOR WINDING MACHINES.

Application filed November 2, 1925. Serial No. 66,224.

This invention relates to improvements in
yarn winding machines more particularly of
that type known as spoolers, in which the
yarn is unwound from a yarn carrier, usu-
ally a bobbin, and onto a yarn receiver, usu-
ally in the form of a large spool.

The object of the invention is to provide
efficient means for controlling the yarn as it
passes from the yarn carrier to the yarn re-
ceiver and so that the yarn will be drawn off
from the yarn carrier without ballooning
and in a regular, even manner and so that the
requisite tension shall be applied to the yarn
to prevent kinking and to insure the yarn
being laid regularly and evenly upon the
yarn receiver.

The object of the invention is further to
provide a mechanism of this type in which
the tension upon the yarn may be readily
controlled and adjusted according to the
conditions.

The object of the invention is further to
provide a mechanism of this type which will
not interfere with the ready placing of the
yarn carrier in, and removing it from, position
in the machine.

These and other objects and features of
the invention will appear more fully from
the accompanying description and drawings
and will be particularly pointed out in the
claims.

Since the general construction and opera-
tion of winding machines such as spoolers are
well known and familiar to those skilled in
the art, and since the invention relates only
to certain features of such machines, it is
only necessary here to illustrate and de-
scribe those portions of an ordinary type of
winding machine or spooler which are neces-
sary to a disclosure of a preferred form of
the present invention.

In the drawings:

Fig. 1 is a transverse sectional view of a
portion of a spooler sufficient to illustrate
the application of the present invention.

Fig. 2 is a top plan view of the support
for the yarn carrier and its connected parts.

Fig. 3 is an end elevation looking along
the axis of the yarn carrier of the construc-
tion shown in Fig. 2.

Fig. 4 is a view in perspective of a roll
such as employed in connection with the in-
vention.

Only a small portion of a spooler is shown

comprising a part of one of the side frames 55
1, the spindle rail 2 and the rod 3 extending
between the side frames, the usual traverse
rod 4 and one of the spools 5 mounted upon
a spindle rotated by one of the usual whirls 6.

As usual in these machines, a separate 60
stand or support is provided for each yarn
carrier and one such embodying the inven-
tion in a preferred form is here shown. This
support or stand comprises two frame mem-
bers 7 and 8 having longitudinal tongue and 65
groove connections so that the frame may be
extended longitudinally. Bolts 9 passing
through slots 10 in the frame member 7 and
then through the frame member 8 serve to
hold the frame members in adjusted position. 70
The frame member 7 at its inner end is
formed into a yoke-shaped clamp 11 engag-
ing the rod 3 and a set screw 12 passing
through one jaw of the clamp serves to hold
the support in fixed position with respect to 75
the frame of the machine. The frame mem-
ber 7 is also extended laterally to form a
base 13 for a spindle 14 upon which is mount-
ed the yarn carrier herein shown as a bob-
bin 15 upon which is wound the mass of yarn 80
16 with the weft or filling wind.

A shaft 17 extends alongside of the spindle
14 and is journalled at its outer end in a
bearing 18 at the end of an arm 19 project-
ing from the frame member 8, while at the 85
other end this shaft slides and rotates in a
projection or arm 20 extending from the
frame member 7. This shaft 17 at its outer
end has secured thereto an arm 21 provided
with a guide eye or notch 22, which notch 90
is normally in line with the axis of the spin-
dle 15. To maintain the yarn guide in this
position, the arm 21 is provided with a
shoulder 23 resting against a lug 24 on the
arm 19. This yarn guide directs the yarn 95
after it leaves the yarn carrier in its path
through the tension mechanism.

The shaft 17 is provided with a plurality
of collars 25 adjustably mounted upon and
lengthwise of the shaft 17 by the set screws 100
26. A plurality of fingers, preferably
formed of wire, are pivotally mounted on
the shaft 17 and properly spaced by these
collars 25. These fingers 27 are somewhat
curved at their ends to conform to the shape
of the yarn mass and are wound to form
spiral hubs 28 fitting the shaft 17. These
fingers rest lightly by gravity on the yarn

mass and act to prevent ballooning of the yarn as it is drawn off from the yarn carrier and act to insure that the yarn shall be drawn off evenly and smoothly and without 5 kinking.

A rod 29 is mounted at its outer end in the yarn guide arm 21 and extends parallel with the shaft 17 beneath the fingers 27 and passes at its other end through an arm 30 10 adjustably secured by the set screw 31 on the shaft 17. Thus it will be seen that whenever it is desired to doff the yarn carrier or remove it from its position on the spindle, the yarn guide arm 21 will be swung upwardly and at the same time the rod 29 will swing the fingers 27 clear of the yarn mass. When a yarn carrier is placed upon its spindle and the yarn guide returned to guiding position, the fingers 27 swing back and 15 rest upon the yarn mass.

The frame member 8 is provided near its outer end with a lateral projection 32 secured in place by a nut 33 threaded thereon. This projection is so located that the yarn 25 passing from the yarn carrier and guided by the eye 22 passes over the middle of this projection on its way from the yarn carrier to the yarn receiver. A second yarn guide 34 may also be employed and is shown as a 30 notched plate secured by the bolt 35 to the frame member 8 and directly in front of the projection 32.

A roll guide is provided immediately 35 above the projection 32 and is shown as in the form of a rectangular well 36 formed as a part of the frame member 8 and extending vertically above the projection 32. This well is open at the top and bottom and preferably 40 also throughout the middle of one side, as shown at 37. A curved flange 38 projects from the well and with the curved end of the projection serves to direct the yarn over the projection and make the device self-threading.

45 A plurality of rolls are provided of a size to fit easily within the well 36 and of dimensions such that the axes of the rolls extend transverse to the yarn path or parallel with the axis of the projection 32. 50 These rolls are superimposed or stand one above the other in the well and are free to rotate and to rise and fall in the well. These rolls may be varied in weight, and this variation is readily accomplished by removing 55 more or less of the central portion of the roll. One such roll 39 is shown separately in Fig. 4. The lowermost roll rests directly on top of the yarn as it passes over the projection 32. Consequently a rolling pressure 60 is produced upon the yarn and the amount of this pressure is governed by the number and weight of the rolls placed in the well. This mechanism acts very efficiently to produce

the requisite tension on the yarn and to prevent kinking of the yarn and insures an even and steady feed of the yarn to the yarn receiver or spool, notwithstanding the fact that the yarn is drawn from a weft wound bobbin and consequently leaves the yarn carrier with a variable speed.

70 The support for the yarn carrier is readily adjustable longitudinally by the means described, thus enabling yarn carriers or bobbins of any length to be employed.

Having thus described the invention, what 75 is claimed as new, and desired to be secured by Letters Patent, is:

1. A yarn winding machine comprising a yarn carrier mounted on a fixed support, a rotating yarn receiver to draw yarn from the yarn carrier, a projection from said support over which the yarn passes from the yarn carrier to the yarn receiver, a roll guide above the support, one or more superimposed rolls free to rotate and to rise and fall in said guide with their axes transverse to the yarn path and acting by gravity to produce on the yarn a rolling pressure governed in amount by the number and weight of the rolls, a yarn guide for the yarn as it leaves the yarn carrier movable into and out of position to direct the yarn in its path over the projection and beneath the rolls, a plurality of pivotally mounted fingers resting on the yarn mass on the yarn carrier and acting to prevent ballooning of the yarn and to cause the yarn to be drawn evenly from the yarn carrier, and means operated by the yarn guide when it is moved out of position and acting to swing the fingers clear of the yarn mass.

2. A yarn winding machine comprising a supporting stand fixedly mounted from the machine frame, a filling carrier supporting spindle on said stand, a shaft mounted in the stand alongside the spindle, and a plurality of fingers pivotally mounted independently on said shaft and resting on the yarn mass on the yarn carrier and acting to prevent ballooning of the yarn and to cause the yarn to be drawn evenly from the yarn carrier.

3. A yarn winding machine comprising the construction defined in claim 2, together with a yarn guide mounted on the end of said shaft, and a rod extending from said yarn guide parallel with the shaft and beneath the fingers, whereby when the yarn guide is rocked on the shaft to move it out of position and permit doffing of the yarn carrier from its spindle, the fingers will be lifted away from the yarn carrier.

In testimony whereof, we have signed our names to this specification.

ALONZO E. RHOADES.
ARTHUR S. JOHNSON,
